UNITED STATES PATENT OFFICE.

BENJAMIN R. VAN KIRK, OF PHILADELPHIA, PENNSYLVANIA, ASSIGNOR TO THE BALDWIN LOCOMOTIVE WORKS, OF PHILADELPHIA, PENNSYLVANIA, A CORPORATION OF PENNSYLVANIA.

SINGLE TRUCK.

1,148,344.

Specification of Letters Patent. Patented July 27, 1915.

Application filed December 26, 1914. Serial No. 879,102.

To all whom it may concern:

Be it known that I, BENJAMIN R. VAN KIRK, a citizen of the United States, residing in Philadelphia, Pennsylvania, have invented certain Improvements in Single Trucks, of which the following is a specification.

One object of my invention is to provide a single truck in which the top plate is rigidly secured to the car body with a long spring base which will prevent galloping or longitudinal rocking.

A further object of the invention is to design the truck so that comparatively light longitudinal beams are used which are mounted directly on the boxes.

A still further object of the invention is to distribute the springs so that they will support the bar at intervals.

Another object of the invention is to provide means for hanging the brake beam directly from the longitudinal beams.

In the accompanying drawings, Figure 1 is a side view of a single truck, illustrating my invention; Fig. 2 is a plan view of one-half of the truck; and Fig. 3 is an enlarged sectional view on the line *a—a*, Fig. 2.

The truck to which my invention relates is what is known as a single truck to which the car body is directly secured and which is not swiveled and the wheel base is such that it will readily pass around curves without swiveling.

Referring to the drawings, 1 is a plate which is rigidly secured to the car body and extends a considerable distance beyond the wheels, as shown in Fig. 1; the car being shown by dotted lines in said figure.

2, 2 are the pedestals which are bent to form upper and lower flanges 3 and 4. The upper flanges are rigidly secured to the plate 1 by rivets, bolts, or other fastenings. Tie rods 5 are secured to the lower flanges of the two inner pedestals so as to connect them rigidly together.

6, 6 are diagonal braces connecting the lower flanges of the outer pedestals to the plate 1, as clearly shown in Fig. 3, and tie plates 7 extend from one pedestal to another of each set, the whole being secured by bolts or rivets, as desired.

8 are liners and 9 are the boxes which are mounted between the pedestals.

10, 10 are the axles.

11, 11 are longitudinal beams, there being

a beam on each side of the pedestals on each side of the truck. These beams rest directly upon the boxes as clearly shown in Fig. 3. The two beams are connected together by bolts 12 near the pedestals and by the bolts 13 at each end of the beam. Suspended from the bolts 12 are the spring carriers 14 in which is formed the lower spring seat 15, the upper spring seat being formed by a block 16 secured to the upper flange of the pedestal and to the plate. Coiled springs 17 are located between the two spring seats, as shown, and aid in carrying the plate and the car body. A semi-elliptical spring 18 is hung from the bolt 13 at each end of the pair of beams. The inner end of this spring rests upon the bearing plate 19 secured to the flange of the brace 6 and the plate, while the outer end rests against a bearing plate 20 on the outer end of the plate 1.

21 is the motor suspension bar mounted on a rod 22 hung from the beams 11 and short coiled springs 23 and 24 are located above and below the suspension bar, as clearly illustrated in Fig. 3.

25, 25 are the brake beams having a head 26 provided with shoes 27 and the beams are suspended by links 28 from the longitudinal beam 11. Pivot pins 29 extend from one beam to the other of each pair and the links are pivoted to these pins.

30, 30 are cross rods extending from one side tie rod to the other and not only act as braces, but may support any mechanism which is carried by the truck.

I claim:

1. The combination in a single truck, of a longitudinal plate at each side of the truck to which the body of the car is rigidly secured; pedestals depending from the plate; means for bracing the lower portions of the pedestals; boxes mounted between each pair of pedestals; axles in the boxes; two longitudinal beams on each side of the truck, one beam being on the outer side of the pedestals and the other on the inner side thereof; spring carriers suspended from the beams; springs mounted between the spring carriers and the plate; springs hung from the outer ends of the beams and supporting the outer end of the plate.

2. The combination in a single truck, of two longitudinal plates, one mounted on each side of the truck and to which the body of the car is secured; pedestals rigidly se-

- cured to the plates; braces at the lower ends of the pedestals connected to the plates; two pairs of longitudinal beams arranged on edge at each side of the truck, one beam of 5 each pair being on the outer side of the pedestals and the other on the inner side thereof, said beams extending beyond the pedestals; spring carriers located between the beams close to each side of each pair of pedestals; 10 coiled springs mounted between the carriers and the plate; and semi-elliptic springs located between the beams at the outer ends and hung therefrom and bearing upon the outer ends of the plate.
- 15 3. The combination in a single truck, of two longitudinal plates arranged to be secured to the body of a car; a series of pedestals having upper and lower flanges, the upper flanges being secured to the under side 20 of the plate; braces and tie rods secured to the lower flanges of the pedestals; boxes located between the pedestals of each set;

axles in the boxes; two pairs of longitudinal beams at each side of the truck, one beam of each pair being on the outer side of the pedestals and the other beam being on the inner side thereof; spring carriers located between the beams on each side of each set of pedestals; coiled springs mounted between the spring carriers and the upper flanges of the 30 pedestals; a semi-elliptical spring located at each end of each pair of beams and suspended from said beams, the outer free end of each spring resting on the under side of the outer end of each plate and the inner end of 35 each spring bearing upon the plate at a point near the pedestals.

In testimony whereof, I have signed my name to this specification, in the presence of two subscribing witnesses.

BENJAMIN R. VAN KIRK.
